RAZOR HANDLE

Martin Glaberson, Stratford, and George L. Schick, Trumbull, Conn., assignors to Warner-Lambert Company, Morris Plains, N.J.

Filed Feb. 15, 1973, Ser. No. 332,960

Term of patent 14 years

Int. Cl. D28—03
U.S. Cl. D95—3 A

Fig. 1

Fig. 2

Fig. 3

Fig. 4

Fig. 5

FIG. 1 is a front elevational view of a razor handle showing our new design;

FIG. 2 is a rear elevational view thereof;

FIG. 3 is a side elevational view thereof, the side not shown being a mirror image of that shown in FIG. 3;

FIG. 4 is a top plan view thereof; and

FIG. 5 is a bottom plan view thereof.

We claim:

The ornamental design for a razor handle, as shown and described.
